US00D476368S

(12) **United States Design Patent**
Suzuki

(10) Patent No.: **US D476,368 S**
(45) Date of Patent: ** Jun. 24, 2003

(54) **TAPE DISPENSER HAVING A
TRANSPARENT CASING**

D447,175 S * 8/2001 Blom et al. D19/46
D452,273 S * 12/2001 Blom et al. D19/46

(75) Inventor: **Kazuhiko Suzuki**, Kanagawa (JP)

* cited by examiner

(73) Assignee: **Tombow Pencil Co., Ltd.**, Tokyo (JP)

Primary Examiner—Martie K. Holtje

(**) Term: **14 Years**

(74) Attorney, Agent, or Firm—Birch, Stewart, Kolasch & Birch, LLP

(21) Appl. No.: **29/166,520**

(57) **CLAIM**

(22) Filed: **Aug. 30, 2002**

The ornamental design for a tape dispenser having a transparent casing, as shown and described.

(30) **Foreign Application Priority Data**

DESCRIPTION

Mar. 1, 2002 (JP) 2002-005475

(51) LOC (7) Cl. **19-02**

(52) U.S. Cl. **D19/69; D19/67**

FIG. 1 is a front view of the tape dispenser having a transparent casing showing my new design with a head cover in a retracted position for exposing an application head;
FIG. 2 is a right side view thereof;
FIG. 3 is a left side view thereof;
FIG. 4 is a rear view thereof;
FIG. 5 is a top view thereof;
FIG. 6 is a bottom view thereof;

FIG. 7 is a front view similar to FIG. 1, with the head cover in an advanced position for covering the application head;

FIG. 8 is a perspective view thereof in a position during use with the head cover in the retracted position for exposing the application head; and,

FIG. 9 is a perspective view similar to FIG. 8, with the head cover in the advanced position for covering the application head.
